UNITED STATES PATENT OFFICE.

FREDERICK WINK, OF PHILADELPHIA, PENNSYLVANIA, ASSIGNOR TO
THOMAS DOLAN AND R. WILLIAMS, JR., OF SAME PLACE.

DESIGN FOR SHAWL.

Specification forming part of Design No. 6,389, dated February 11, 1873.

To all whom it may concern:

Be it known that I, FREDERICK WINK, of the city and county of Philadelphia, State of Pennsylvania, have invented a Design for a Shawl-Pattern, of which the following is a specification:

The figure in the accompanying drawing fully represents my design, which consists of alternate stripes A and B upon a plain or mottled ground, C. The stripes A and B are composed of minor stripes of varying widths, and of different shades or colors, the stripe A having a central rib, *a*, of the peculiar char-

acter clearly represented in the drawing, while the stripe B has a central checkered rib, *b*.

Irrespective of the colors employed, I claim—

1. The design for the stripe A, as shown.
2. The design for the stripe B, as shown.
3. The design for the whole pattern, as shown.

In testimony whereof I have signed my name to this specification in the presence of two subscribing witnesses.
